Patented Jan. 13, 1920.

WITNESS:

E. Q. Ruppert

J. J. Martinka
INVENTOR.

BY

Victor J. Evans
ATTORNEY.

UNITED STATES PATENT OFFICE.

JOSEPH J. MARTINKA, OF NEWARK, NEW JERSEY.

SURGICAL APPLIANCE FOR WOMEN.

1,328,176.

Specification of Letters Patent. Patented Jan. 13, 1920.

Application filed September 13, 1919. Serial No. 323,455.

To all whom it may concern:

Be it known that I, JOSEPH J. MARTINKA, a citizen of the United States, residing at Newark, in the county of Essex and State 5 of New Jersey, have invented new and useful Improvements in Surgical Appliances for Women, of which the following is a specification.

The object of my present invention is the 10 provision of simple, efficient and easily applied means for preventing bed wetting by women and girls afflicted with bladder weakness or any other disease that prevents them from controlling the discharge of urine.

15 To the attainment of the foregoing, the invention consists in the peculiar and advantageous appliance hereinafter described and definitely claimed.

In the accompanying drawings, hereby 20 made a part hereof:

Figure 1 is a general view showing the device constituting the preferred specific embodiment of my invention combined with the straps which are preferably, though not 25 necessarily, employed in the attachment of the device to a patient.

Fig. 2 is a longitudinal section through the clamping device *per se*.

Fig. 3 is a cross-section of the same.

30 Fig. 4 is an enlarged detail section illustrative of the means for strongly though yieldingly pressing the labia-engaging portions of the clamp jaws toward each other.

Similar numerals of reference designate 35 corresponding parts in all of the views of the drawings.

My novel device is in the nature of a clamp, and is designed to be applied in and to engage the labia of the vulva in such manner as to compress and thereby effectually 40 close the eduction orifice portion of the urethra, thereby preventing bed wetting.

As illustrated the device comprises two 45 jaws 1. These jaws are preferably, though not necessarily, of celluloid for the sake of combined lightness and strength, and each is provided with an intermediate portion 2 that is longitudinally concavo-convex, the 50 convex side being outermost. On the inner sides of their forward portions the jaws are provided with serrations 3 or are otherwise roughened to better enable them to engage and retain their hold on the labia mentioned. Being of celluloid the jaws 1 are resilient, 55 and their rear side by side portions are con-

nected together through the medium of rivets 4. At a point slightly in advance of the said rivet connection the jaws are connected together by one or two elastic bands 5 which are arranged in apertures of and 60 extend between the jaws and have the effect of normally though yieldingly holding the jaw portions 3 together with a view to facilitating the proper positioning of the device on a patient. Connected to one of the 65 jaws and extending loosely through an aperture in the other jaw is a transverse threaded bolt 6, and mounted on the said bolt is a nut 7 between which and the opposed jaw is loosely mounted a washer 8. The scheme of 70 my invention contemplates the opening of the jaws against the action of the elastic bands 5, the placing of the said jaws with the labia mentioned between them, the initial retention of the jaws on the portions of 75 the said labia at the opposite sides of the eduction orifice of the urethra by the said elastic bands 5, and the subsequent compression of the labia and the eduction portion of the urethra between the jaws in a 80 powerful manner by turning the nut up on the bolt or otherwise subjecting the jaws to pressure.

The attaching straps 9, 10 and 11 are preferably applied to the clamp device in the 85 manner shown. Said straps are also, by preference, elastic in character to conduce to the comfort of the patient, and are equipped with appurtenances 12, 13 and 14 or fastener members of any other approved 90 type so that the device may be readily and securely fastened to the body of the patient.

It will be apparent from the foregoing that notwithstanding the facility with which my novel device may be applied, the 95 device may be depended upon to prevent bed wetting by a woman or a female child.

Having described my invention, what I claim and desire to secure by Letters Patent, is:

1. A device for preventing bed wetting by a woman or female child, comprising jaws formed of thin resilient material and having concavo-convex intermediate portions, flat opposed rear portions connected together 105 and forward portions the inner or opposed faces of which are roughened, an elastic band arranged in and connecting said rear portions of the jaws and tending to yieldingly hold the forward portions thereof together, 110

and means connecting the intermediate portions of the jaws and adjustable to positively press said jaws together.

2. A device for preventing bed wetting by a woman or female child, comprising resilient jaws of plate-like form, means connecting the rear portions of said jaws to-

gether in opposed relation, resilient means for holding the forward portions of the jaws under yielding pressure against labia, 10 and means connecting the jaws and adjustable to subject the same to positive pressure.

In testimony whereof I affix my signature.

JOSEPH J. MARTINKA.
